MAGNETIC DISK FILE

Clifford I. Dawson and Dallas G. Molerin, San Jose, Calif., assignors to International Business Machines Corporation, Armonk, N.Y.

Filed Dec. 17, 1969, Ser. No. 20,529

Term of patent 14 years

Int. Cl. D14—02

U.S. Cl. D26—5

FIG.2

FIG.1

FIG. 1 is a front perspective view of a disk file according to this invention; and

FIG. 2 is a top view of the novel design of the disk file of FIG. 1.

The side not shown is like the side shown while the back is conventionally flat and unornamented.

We claim:

The ornamental design for a magnetic disk file, as shown and described.
